CLAIM

The ornamental design for an electric cleaning brush handle as shown and described.

DESCRIPTION

FIG. 1 is a front, left and top perspective view of an electric cleaning brush handle showing my design;

FIG. 2 is a rear, right and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof; and,

FIG. 7 is a top plan view thereof.

The broken lines immediately adjacent to the shaded areas depict the bounds of the claimed design, while all other broken lines are directed to environment. The broken lines form no part of the claimed design.

1 Claim, 7 Drawing Sheets(56)
